UNITED STATES PATENT OFFICE.

WILLIAM C. BANKS, OF NEW YORK, N. Y.

BATTERY.

SPECIFICATION forming part of Letters Patent No. 787,716, dated April 18, 1905.

Application filed October 22, 1904. Serial No. 229,535.

To all whom it may concern:

Be it known that I, WILLIAM C. BANKS, a citizen of the United States of America, residing at New York, in the county and State of New York, have invented certain new and useful Improvements in Batteries, of which the following is a specification, reference being had to the accompanying drawings, forming part of the same, in which—

10 Figure 1 is a central vertical sectional view of one cell of a battery embodying my invention. Fig. 2 is a plan view of the element-supporting base. Fig. 3 is a perspective view of a form of tube I prefer to employ. Fig. 15 4 is a similar view of a supporting and insulating plate. Fig. 5 is a similar view of the current-collecting cup, which also constitutes the base and inner wall of the depolarizer basket or holder. Fig. 6 is a similar view of 20 the depolarizer-basket—*i. e.*, its outer wall—and Fig. 7 is a similar view of a modification in which the cup and the outer wall are united.

25 My invention consists in constructing the various parts that go to make up a primary battery in such form and arranging them in such relation that greater efficiency is attained in the use of elements already well known, and as a further feature the said construction permits the ready and convenient assembling 30 of the parts and their ready recharging as well as renders them susceptible of convenient packing for shipment.

35 In the embodiment of this invention here shown, J is the jar, which may be of glass or any other suitable material. The one represented is about six by eight inches. In this jar I place a base or support S in the form of a porcelain tripod, with a central orifice O and feet F, having (preferably) knees n to carry 40 the zinc Z. The interior walls of the orifice O are provided with the grooves g of a bayonet-joint, as shown.

45 T is a porcelain tube of a size adapted to fit neatly (but not too tightly) in the orifice O and provided with lugs l on opposite sides adapted to take into the grooves g and in connection with their walls to lock the parts S and T together. An indentation q' is preferably left at the top to leave space for the head 50 of the binding-screw. A further lug or col-

lar l' is sometimes formed on tube T at about the level of the upper edge of the zinc to assist in supporting the upper parts.

P is an insulating and supporting plate, usually a flat perforated disk of porcelain 55 with an orifice O' to permit its being put over the end of the tube T and passed down till it rests upon the top of zinc Z or lug l', one or both. Its use as a support is not indispensable; but some insulation, either a vacant or 60 occupied space, must exist between the zinc and the depolarizer-basket, and this plate answers exceedingly well and at the same time adds materially to the strength of the combination. 65

Next in order is the cup C, formed as a hollow tube t of a size to accommodate tube T and a length sufficient to extend above the intended level of the solution to be used, with an annular disk or base b (of such area as is 70 desired for the depolarizer-holder) secured to the tube t and provided with an upwardly-extending flange f, projecting from its periphery. At its upper end it is provided with a binding-screw s. 75

B is the remaining wall of the depolarizer-basket. It may be a cylinder of perforated tin of suitable width set in cup C or it may be simply a strip of tin bent into a cylindrical form and then placed in the cup. A wire w, 80 riveted to the zinc, as shown, and then led down to the lower end of the tube T and through that tube, constitutes the other terminal.

Upon filling the basket with a depolarizer—85 such, for instance, as black oxid of copper—and pouring a suitable energizing solution into the jar the battery is ready for use.

If preferred, the cup C and basket portion B may be soldered or otherwise secured together, as shown in Fig. 7; but for some purposes the other form is preferable. 90

It will be noticed that the parts are all so constructed that, like a knockdown box, they may be readily taken apart and conveniently 95 stowed in packing, a feature of great moment when breakage and freight are under consideration. Parts that pack closely and are without a multiplicity of corners not only take less space themselves, but they need less ma- 100

- terial about them to insure their safety and space is gained in both ways, thereby materially reducing the charges for transportation as well as the loss from breakage. Not only so, but the porcelain parts may be much more easily molded when as shown than if they were in one piece. Again, when the zinc and the depolarizer have been spent this battery may be most conveniently recharged.
- 10 One may seize the upper end of tube T and readily remove the parts from the jar, then draw the basket off the tube, and pull the perforated strip B from its place, where the depolarizer may be easily shaken from the cup.
- 15 The zinc may as readily be removed and a new one placed, removing the disk for the purpose.

The tedious cleaning out of baskets to which the depolarizer has become fastened is avoided, since the piece B may be thrown away, its cost being but a very little. Beyond and above these points, however, lies the fact that the cup portion of the basket is a much more efficient current-collector than is the part B, and a depolarizer-basket formed wholly of such material as that of B with a terminal secured to its upper outer edge gives by no means such good results, electrically considered, as the form having cup and perforated wall combined. The location of the depolarizer above the zinc is also a point of merit, and the leading of the circuit-wire from the zinc to and through the porcelain tube is another detail which still further obviates objectionable action in the cell.

What I claim as my invention, and desire to secure by Letters Patent, is—

1. In a battery the combination of a jar, an insulating-support for the positive element, an insulating-tube extending upward from said support to a point above the intended solution-line, a positive element resting on said support, a depolarizer-basket, insulated from the positive element and provided with a terminal and a connection leading from the positive element to and through said insulating-tube, all substantially as set forth.

2. In a battery the combination of a jar, an insulating-support for the positive element, an insulating-tube matched to fit to and lock with said support and extending upward from said support to a point above the intended solution-line, a positive element resting on said support a depolarizer-basket, insulated from the positive element and provided with a terminal and a connection leading from the positive element to and through said insulating-tube all substantially as set forth.

3. In a battery, the combination of a jar, an insulating-zinc support, a zinc thereon, an insulating-tube extending upward from said support, an insulating-plate above the zinc and around the tube, a depolarizer-basket with outer perforated walls, inner walls surrounding said insulating-tube and a base resting above the insulating-plate and completing the basket inclosure, together with terminals and connections, all substantially as set forth.

4. In a battery, the combination of a jar, an insulating-zinc support, an insulating-tube, locked to but detachable from the zinc-support, and extending from said support to a point above the intended solution-line, a zinc surrounding said tube and resting upon said support, an insulating-plate placed over the zinc and about the tube, an annular depolarizer-basket placed on said plate and surrounding said tube and composed of a tube about the insulating-tube, an outer wall and a base extending from the inner to the outer wall, a connection leading from the zinc to the lower part of the insulating-tube and up through said tube and a terminal secured to the upper end of the tube portion of the depolarizer-basket, all substantially as set forth.

In testimony whereof I have signed my name to this specification, in the presence of two subscribing witnesses, this 29th day of September, 1904.

WM. C. BANKS.
